UNITED STATES PATENT OFFICE.

PHILIP LANOUETTE, OF NAUGATUCK, CONNECTICUT.

DESIGN FOR A CARRIAGE-JACK.

SPECIFICATION forming part of Design No. 27,473, dated August 3, 1897.

Application filed May 11, 1897. Serial No. 636,105. Term of patent 7 years.

To all whom it may concern:

Be it known that I, PHILIP LANOUETTE, a citizen of the United States, residing at Naugatuck, in the county of New Haven and State 5 of Connecticut, have invented and produced a certain new and original Design for Carriage-Jacks; and I do declare the following to be a full, clear, and exact description of the invention, such as will enable others skilled 10 in the art to which it appertains to make and use the same.

The invention has relation to a new and original design for a carriage-jack; and it consists of a jack of the configuration and ornamentation shown in the accompanying drawing, in which I have represented the invention in perspective.

The leading features of my design consist 20 in a longitudinal bar 1, having at one end a square socket 2, from which extends, in an oblique direction, an extension 3, having a

head 4, provided with apertures 5 and 6 of different areas, a notch 8 at one corner, a laterally-projecting arm 9, having an elongated aperture 10, and an angular recess 11. Projecting in the opposite direction from this head 4 is an arm 12, provided with a lip 13, having a serrated face 14. Formed at the rear end of the arm is an ear 15, having an angular recess 16, and projecting in an oblique direction from this end of the bar 1 is an arm 17, provided with a forked lower end 18.

What I claim is—

The design for a carriage-jack, as herein shown and described.

In testimony whereof I hereunto affix my signature in presence of two witnesses.

PHILIP LANOUETTE.
